UNITED STATES PATENT OFFICE.

VICTOR H. FAIRLESS, OF TRENTON, TENNESSEE.

SOFT-COLLAR SUPPORT.

1,427,727.

Specification of Letters Patent. Patented Aug. 29, 1922.

Application filed April 23, 1921. Serial No. 463,745.

To all whom it may concern:

Be it known that I, VICTOR H. FAIRLESS, a citizen of the United States, residing at Trenton, in the county of Gibson, State of Tennessee, have invented certain new and useful Improvements in Soft-Collar Supports; and I do hereby declare the following to be a full, clear, and exact description of the invention, such as will enable others skilled in the art to which it appertains to make and use the same.

The present invention relates to improvements in soft collar supports and necktie retainers, and one object of the invention is to provide for the stiffening of the edges and points of soft collars which are apt to wilt and get out of shape and become unsightly.

Another object of the invention is to provide for the support of the necktie within the upper portion of the doubled over soft collar by the same means used to stiffen the edges and points of the collar.

It is a further object of the invention to provide a simple and inexpensive necktie retainer and soft collar support in which the usual standard form of soft collars is not in any way modified, but which involves merely the placing upon the interior of the outer fold of the collar near the front edges and points thereof of a pocket and retaining strap adapted to receive a doubled over piece of celluloid or other material which forms at its upper ends a support to receive the band of the necktie and hold it in the upper portion of the fold of the collar.

With the foregoing and other objects in view, the invention will be more fully described hereinafter, and will be more particularly pointed out in the claims appended hereto.

In the drawings, wherein like symbols refer to like or corresponding parts throughout the several views.

Fig. 1 is a perspective view of a soft collar with one flap thereof turned up to expose the improved soft collar support and necktie retainer;

Fig. 2 is a perspective view with a part broken away and showing a necktie sustained by the improved device;

Fig. 3 is a sectional view taken on the line 3—3 in Fig. 2; and

Fig. 4 is a perspective view of the retaining strip.

Referring more particularly to the drawings, 1 and 2 designate respectively the inner and outer folds of a double soft collar which is usually made with the points 3 and 4 at its front portion, and 5 represents a necktie shown in Fig. 2 within the collar and having a band 6 which fits about between the folds 1 and 2 of the collar in the usual manner.

The invention aims to hold the free edges of the outer fold 2 of the collar in a stiff and straight condition at all times to avoid the unattractive effect of wilting, and to prevent the wrinkling of the soft material of the collar at the front where conditions of this kind are most apt to occur which make the collar unsightly. The invention also provides for the holding of the neck band 6 of the necktie at a suitable elevation whereby the necktie knot 7 carried by the band may be supported against sagging, and for this reason may always present a neat appearance.

The invention involves the provision of a pocket 8 provided by a rectangular flexible strip sewed along its bottom and longitudinal edges to each inside face of the outer fold 2 of the collar near the free edge and the point thereof. The upper edge of the rectangular flexible strip forming the pocket 8 is left free so as to provide an open mouth for the pocket in which a stiffening strip of celluloid or other material is placed. This stiffening strip is preferably formed of two legs 9 and 10 formed by doubling over as at 11, a thin, light piece of celluloid or suitable material so that the two ends overlie one another and lie in substantially parallel relation, one end 12 being preferably slightly longer than the other so as to readily separate it from the opposite free end.

Additionally, there is provided a retaining strap 13 on each inside face of the outer fold 2 of the collar above and in line with the pocket 8 and spaced apart from the open mouth of said pocket, the retaining strap 13 being sewed along its longitudinal edges to the fold 2 but being left free at its ends so as to be completely open to permit the passage therethrough of the stiffening strip.

In use, pockets 8 and retaining straps 13 having been secured by stitching or otherwise to the outer fold 2 of the soft collar in the positions indicated best in Figs. 1 and 2

and previously described, the stiffening strips are secured therein by first separating the free ends of the strips and inserting one of the free ends, first into the space between the 5 pocket 8 and the retaining strap 13, and then moving one of the legs, for instance 9, upwardly through the retaining strap 13 until the doubled over end 11 of the strip is capable of being inserted downwardly into 10 the mouth of the pocket 8.

The strip is thus moved downwardly until the major portion thereof lies within the pocket 8 and one end, for instance 12, lies outside of the retaining strap 13, while the 15 other free end of the strip is held fast within the retaining strap 13. The necktie band 6 is engaged between the retaining strap 13 and the outer free end of the stiffening strip and is supported by the bight 14 provided 20 by the lower portion of this outermost part of the retaining strip where it starts to enter the mouth of the pocket 8.

The fabric material of which the pocket 8 and the retaining straps 13 are made is of course of a light, inexpensive character, and it is provided on the collar fold in an inexpensive way. Likewise the retaining strip, which may be of celluloid, is very thin and utilizes only a small amount of this material 30 and is therefore relatively cheap. The strip may be removed whenever the collar is to be laundered and is subsequently replaced before wearing in the manner heretofore described. It will be appreciated from the 35 foregoing that the device is an extremely simple one capable of being attached to present styles of soft collars without any modification or alteration in the construction thereof, and in which the edges and 40 points of the soft collar are maintained in a fresh and unwilted condition at all times, and moreover the necktie knot 7 is held against sagging so that the whole presents throughout the period of wearing a neat and 45 attractive appearance which is not possible

to maintain for any length of time where a stiffener of this character is not employed.

It is obvious that various changes and modifications may be made in the details of construction and design of the above specifically described embodiment of this invention without departing from the spirit thereof, such changes and modifications being restricted only by the scope of the following 55 claims.

What is claimed is:—

1. An article of manufacture for use in connection with soft collars and the like comprising a strip of material adapted to be secured along its bottom and sides to the inner surface of a fold of a double collar whereby to provide with the collar a pocket being open at its top portion, a strap also adapted to be secured to the same fold of the collar and spaced slightly from the open mouth of the pocket, and a strip of suitable material folded upon itself and adapted to lie with its folded portion within the pocket and project without the same, one free end portion of the strip lying within the strap, the other free end of the strip extending on the exterior of the strap, substantially as described.

2. In combination with a collar having inner and outer folds, of a pocket secured to the inner face of the outer fold near the edge of the collar and being closed at its sides and bottom and open at its top portion, a retaining strap also secured to the inside face of the outer fold of the collar in spaced relation to said pocket, and a strip of celluloid folded upon itself and having the folded end lying in and supported by said pocket and with the inner free end portion extending within said strap, the outer free end portion of the strip lying outside of the strap and adapted to slidably receive a necktie, substantially as described.

VICTOR H. FAIRLESS.
